LOCKSTITCH SEWING MACHINE

Paul D. Pryor, Chicago, Ill., assignor to Union Special
Machine Company, Chicago, Ill., a corporation of
Illinois

Filed Nov. 27, 1957, Ser. No. 699,219

14 Claims. (Cl. 112—184)

This invention relates to lockstitch sewing machines and more particularly those of the industrial type intended for high speed operation. Machines of this character are provided with one or more rotary hooks, each having a rotary component within which is mounted a substantially stationary bobbin carrier. The latter retains a bobbin which provides the stitch locking thread around which the needle thread loop is carried by the rotary component. In a machine of this type there is usually provided a fixed shoulder or abutment on the frame of the machine cooperating with a shoulder provided on the bobbin carrier to prevent rotation of the latter with the rotary component. Means are also provided for turning the bobbin case holder through a small angle, at the proper time, counter to the frictional drag of the rotating hook. This is to open up a gap between the shoulders mentioned and thus permit the free passage of the needle thread loop around the bobbin carrier and between those shoulders which normally prevent rotation of the bobbin carrier with the rotary component.

The present invention is primarily concerned with the provision of improved means for turning the bobbin carrier, at the proper time, counter to the frictional drag of the rotary hook so that the shoulder on the bobbin carrier is shifted slightly away from the fixed shoulder carried by the frame of the machine to thus allow free passage of a leg of the needle thread loop between these shoulders. Devices heretofore provided for this purpose have involved an oscillatory arm arranged to engage a triangular projection on the bobbin carrier for turning the latter at the appropriate time counter to the frictional drag mentioned. Such devices have been subject to the objection that considerable noise is created as an incident to the striking of the oscillatory arm against the cooperating surface of the bobbin carrier. Also the constant striking of the oscillatory arm or finger against the surface on the bobbin carrier has led to excessive wear which has required frequent replacement of parts. Moreover, a limit has been imposed upon the speed of operation of the machine due to the inertia forces involved in oscillating the arm or finger mentioned.

The present invention largely overcomes these objections to prior devices and provides substantially noiseless means, which is subject to considerably less wear and capable of operation at considerably higher speeds than prior devices, for turning the bobbin carrier a sufficient distance to enable the free passage of the needle thread loop between the specified shoulders. For this purpose the turning of the bobbin carrier is effected by a rotating cam arranged to engage a projection on the bobbin carrier and turn the same counter to the frictional drag of the rotary hook, at the proper time. The arrangement is such, moreover, that a suitable clearance is provided at the appropriate time between the constantly rotating cam and the projection on the bobbin case holder so that the needle thread loop may pass

2

freely between these parts when required during the stitch forming cycle.

In achieving the foregoing ends a number of important features are incorporated in the machine in accordance with the invention. The rotary cam mentioned may be driven in a variety of different ways. It may be driven by suitable connections from the rotary hook shaft of the machine or it may be driven by independent connections from the main shaft in the base of the machine which also drives the hook shaft. When the cam carrying shaft is driven from the hook shaft this may be either through a toothed belt cooperating with toothed sprockets or it may be through appropriate gearing. A belt connection between the cam shaft and the hook shaft is generally preferred because it eliminates the noise incident to the operation of gearing. Also in the preferred embodiment of the invention, the arrangement is such that the cam carrying shaft is rotated at only half the angular speed of the hook shaft. Thus, in a machine in which the hook shaft is rotated through two revolutions for each revolution of the main shaft and for each reciprocation of the needle, the cam will be rotated only one revolution for each reciprocation of the needle. As will be understood, alternate revolutions of the hook are idle so that no opening action is required during such revolutions. However, certain advantages of the invention are obtained even when the cam carrying shaft is revolved at the same angular speed as the hook shaft. The cam may be of substantially the same configuration regardless of which of the two mentioned speeds of rotation are imparted to it.

An important specific feature of the invention is the adjustable mounting of the rotating cam. The construction is such that the cam may be adjusted in a radial or diametral-direction in relation to its supporting and driving shaft and it, together with its supporting shaft, may be adjusted angularly in relation to their driving means, and hence in relation to other driven parts of the machine, such as the rotary hook. By virtue of these adjustments, the timing of the action of the cam may be varied to suit the particular requirements of the work to be performed and the diametral adjustment of the cam makes possible a desirable variation in the extent of the opening action imparted by it to the bobbin carrier and also the amount of the clearance provided between it and the bobbin carrier when the needle loop is drawn between them. This brings about various advantages such as the elimination of the need for small tolerances in the production and assembly of the various parts, the compensation for wear of certain parts, and the adjustment of the opening action to conform, to best advantage, with the requirements of the stitching operation to be performed, depending, for example, upon the character of the threads employed in the production of a line of stitching.

As a further special feature of the invention, the rotary cam and its supporting and driving shaft are preferably so located in relation to the rotary hook carrying shaft and the throat plate of the machine, as well as other elements thereof, that the machine is capable of operation at very high speeds. Thus, the preferred location of the cam and its supporting and driving shaft insures proper passage of the needle thread loop, during high speed operation of the machine, not only through the gap between the shoulders on the bobbin carrier and a fixed part of the machine, such as the throat plate, but also through the gap between the operating surface of the cam and a cooperating projection on the bobbin carrier. For extremely high speed operation of the machine it becomes important to space the second specified gap as far apart as possible from the first in the direction of hook rotation,

On the other hand, where conventional speeds of operation in the neighborhood of 4,000 stitches per minute are satisfactory, the indicated spacing of the two gaps may be less and the particular location of the cam and its supporting and driving shaft becomes less important. It has been found possible under these circumstances to incorporate the new rotary cam device in hook units or saddles of the type heretofore employed, without substantial changes. The special location of the cam for high speed operation of the machine, on the other hand, requires substantial modification of previously existing hook saddles.

The invention is particularly suited for use in vertical axis hook machines having two rotary hooks cooperating with separate needles carried by a reciprocating needle bar. Units constructed in accordance with the invention are such as to make possible the relatively close spacing of the two lines of stitching formed by the two needles and their cooperating vertical axis hooks. This is an important consideration since its adapts the invention for use in machines capable of producing either widely or closely spaced lines of stitching. The two units applied to a machine differ from each other slightly, because of their right and left hand relationship, but in principle they are the same.

While the invention is disclosed herein as applied to a vertical axis hook it may also be applied to a horizontal axis hook. In a vertical axis hook unit the bobbin carrier usually receives the bobbin directly and is sometimes referred to as a bobbin basket. On the other hand, the conventional construction for a horizontal axis hook involves a bobbin case which holds the bobbin and is in turn inserted in a carrier or holder which bears the same relation to the rotating hook body as does the bobbin carrier of the vertical hook unit.

Other objects, features and advantages of the invention will appear from the detailed description of several embodiments of the invention which will now be given in conjunction with the accompanying drawings, in which:

Fig. 1 is a plan view of a portion of the work supporting base of a sewing machine embodying the invention, certain cover plates for said base being removed;

Fig. 26 is a vertical sectional view taken along the line 26-26 of Fig. 24;

Fig. 27 is a bottom plan view of a portion of one of the hook units embodied in Fig. 24 with the bottom closure plate removed and the gearing in the bottom shown in broken lines;

Fig. 28 is a vertical sectional view taken along different vertical planes through the right hand portion of Fig. 24, and

Fig. 29 is a plan view showing the relationship between the two rotary hooks, their related rotary cams, the throat plate and the feed bar of a machine embodying the form of the invention shown in Fig. 24.

The various forms of the invention illustrated in the accompanying drawings have been shown as applied to a sewing machine of the general character illustrated in the patent to Quist, No. 2,329,484, granted September 14, 1943, and the patent to Cottrell, No. 2,712,802, granted July 12, 1955. Thus, it will be understood that the machine comprises a main frame having a work supporting base, a vertical standard and an overhanging arm. A

50 rotary drive shaft extends longitudinally of the base and another rotary drive shaft extends longitudinally of the overhanging arm, these shafts being interconnected for rotation in unison by gearing, or the like, in the vertical standard. In the work supporting base there is also provided a longitudinally extending rock shaft adapted to be rocked or oscillated by suitable connections from the rotary drive shaft in the overhanging arm.

55 Referring now to the drawings, there is shown in Fig. 2 the work supporting base 10 of the machine. In this is mounted for rotation the main lower drive shaft 11, the latter being journaled in bearing sleeves 12 and 13 carried by suitable lugs forming part of the frame. A rock shaft 14 extending longitudinally of the base portion of the frame is arranged to be driven, in the manner explained above, from the main rotary drive shaft in the overhanging arm. One of the rotary hook units embodied in the machine is designated generally at 15, this comprising a frame having a clamping portion 16 arranged to be clamped upon the bearing sleeve 12. The arrangement is such that the unit may be adjusted axially along

the bearing sleeve 12 and clamped in any desired set position. At its opposite side the unit is secured to the base portion of the frame by a screw 17 passing through an elongated slot in the frame of unit 15 and having threaded engagement with the base portion of the main frame. A second rotary hook unit designated generally at 18 is of similar construction to unit 15 but has a slightly different relationship between certain of its parts, so that there is in effect provided a right-hand and a left-hand hook unit, both arranged to be driven directly from the shaft 11. The unit 18 has a clamping portion 19 arranged to be adjusted axially along the bearing sleeve 13. A screw 20 cooperating with a flange at the opposite side of the unit 18, provided with an elongated opening, serves to secure this side adjustably to the base portion of the main frame of the machine.

Referring now to Fig. 6, the unit 15 comprises a frame or saddle 21 having a lubricant containing enclosed housing portion and having upper and lower lateral extensions 22 and 23 in which certain parts are journaled. Thus, a hollow hook shaft 24 is journaled in suitable bushings carried by extensions 22 and 23, this shaft carrying a spiral gear 26 intermediate said extensions. The gear 26 is adapted to mesh with a spiral gear 27 (Fig. 2) secured to the rotary shaft 11 in a manner to permit its axial adjustment along the latter to conform with the adjustment of the hook unit. Gears 26 and 27 are such that two revolutions are imparted to the shaft 24 for each revolution of the shaft 11. At its upper end the shaft 24 carries a rotary hook 28 which, as best shown in Figs. 10, 12 and 13, is provided with a beak 28a adapted to seize a needle thread loop at the appropriate time in a stitch forming cycle. This needle thread loop is indicated at 29 in Fig. 6 and, as shown, extends downwardly from the right-hand one of a pair of needles 30. It will be understood that the other needle shown cooperates in a similar manner with the rotary hook embodied in the unit 18. Within the rotary hook 28 is mounted a bobbin carrier or holder 31 (Fig. 10) having a radially projecting rib cooperating with a groove or raceway in the body of the hook 28. A bobbin 32 is arranged to be carried by the holder 31. A portion of the raceway in the hook body is provided by a removable plate 33 secured by screws 34 to the main hook body. The arrangement is such, as will be explained, that the bobbin case holder 31 is restrained against rotation under the frictional drag of the hook body as the latter is revolved at high speed.

The means for restraining the bobbin holder against rotation with the hook body comprises a projection 35 extending laterally from a flange at the top of the holder. This projection fits into a gap 36 provided between downwardly extending ribs 37 and 38 on the undersurface of a throat plate 39 secured by screws or the like to the base of the main frame. Normally, the frictional drag tending to rotate the bobbin holder, will urge the projection 35 into engagement with the adjacent edge of the rib 37, as shown in Figs. 13 and 15. In order to make it possible to carry the upper leg of the needle thread loop 29 across the top of the bobbin holder, it is necessary to provide a gap between the projection 35 and the rib 37 at the appropriate time. This is indicated in Fig. 12. To accomplish this, the flange at the top of the bobbin holder is provided with a triangular projection 35a arranged to cooperate with a continuously revolving cam 40. The latter is so constructed and arranged as to act upon the projection 35a at the proper time in a cycle of stitch formation to turn the bobbin holder in a direction counter to the frictional force applied thereto by the rotating hook. As shown in Figs. 12 and 14, this reverse movement of the bobbin holder is sufficient to provide the desired gap between the shoulders on projection 35 and rib 37 for the passage of the needle thread loop but preferably not so great as to force the projection 35 into engagement with the rib 38.

Cam 40 is provided with an elongated opening 41

75

arranged to cooperate with a diametral rib 42 extending upwardly from the upper end of a rotary shaft 43. This shaft is provided with an axially extending screw threaded opening 44 at its upper end with which cooperates a screw 45 for securing the cam 40 to the top of the shaft. The opening 44 divides the rib into two sections, as shown in Fig. 4. As will be seen, the arrangement is such that the position of the cam 40 in relation to the shaft 43 may be varied slightly in a diametral direction to either increase or decrease the camming action of the cam 40 on the projection 35a of the bobbin holder. This adjustability of the cam eliminates the need for close tolerances in the production of various parts and also allows take up for wear and assurance that adequate clearance is provided between projection 35 and rib 37 to allow the needle thread loop to pass through the gap in the manner explained. It also insures the provision of an appropriate gap between the periphery of the cam and the cooperating surface of the projection 35a at the proper time to permit the free passage of the needle thread loop between these parts.

For rotating the shaft 43 and cam 40, connections are provided from the hook shaft 24, as best shown in Figs. 2 and 6. These connections comprise a toothed sprocket 46 secured to the shaft 24 adjacent its lower end, a sprocket 47 secured to the shaft 43 adjacent its lower end and a toothed belt 48 interconnecting the sprockets for rotation in unison. In the arrangement disclosed in Figs. 2 and 6 the sprocket 47 is of twice the diameter of sprocket 46 so that shaft 43 is rotated at only half the angular speed of shaft 24. This provides for a single revolution of the cam 40 for each two revolutions of the hook body 28, one of which is an idle revolution, as will be understood. It should be noted that the driving connection between the shafts 24 and 43 is such that these are both revolved in the same direction. This is indicated by the arrows in Figs. 12 and 13, the arrangement being such that the frictional force applied by the cam to the cooperating surface 40 of the projection 35a assists the camming action on the latter in turning the bobbin carrier against the frictional drag imparted by the rotating hook body 28.

The form of the cam 40 and its angular position on the shaft 43, in relation to the angular position of the beak 28a of the hook body 28 at any instant, are such as to bring about the proper timing of the camming action of cam 40 on the bobbin holder depicted in Figs. 12 and 13. To insure the proper timing of this action, and to enable variation of the angular relationship mentioned, the sprocket 47 is secured to the shaft 43 by means of a set screw 47a. By loosening the latter, the shaft 43 and cam 40 may be turned without causing rotation of either of the sprockets or the shaft 24. In this way appropriate timing may be insured for a variety of different seaming operations.

In Fig. 7 there is shown a connection between the shafts 24 and 43 which brings about rotation of shaft 43 at the same angular speed as shaft 24. For this purpose a sprocket 49 secured to the shaft 24 and a sprocket 50 secured to the shaft 43 are of equal diameter and are interconnected by a toothed belt 51 to bring about the result stated. With this arrangement it will be understood that the cam 40 will act upon the projection 35a of the bobbin holder on each revolution 65 of the hook body 28 and hence twice for each reciprocation of the needle bar. Since one of these actions of the cam 40 is an idle one, it is considered preferable, in general, to employ the arrangement disclosed in Fig. 2.

It will be noted by reference to Fig. 13 that that portion of the cam 40 which is opposite the projection 35a on the bobbin holder, shortly after the cam has shifted the bobbin holder in the manner indicated in Fig. 12 and for a suitable period thereafter, is cut away as indicated at 40a. This provides a clearance between the projection 35a and the cam through which the needle

thread loop 29 may be readily passed as the hook beak reaches its loop shedding position. It is important that this gap be provided, in the embodiment of the invention now being described, shortly after the gap between projection 35 and rib 37 has been opened up for the passage of the upper leg of the needle thread loop, since this loop is very quickly carried into the region of the cam 40 after this has occurred. The provision of this cutaway portion of the periphery of cam 40 is particularly desirable when the cam is located in the position shown, for the embodiment of Figs. 1 to 15, in relation to the hook body and the throat plate. As will be explained in connection with another embodiment of the invention, the cutting away of a substantial arc of the periphery of the cam is not necessary when the cam is located in a different position in relation to the parts mentioned.

Unit 18 of the machine illustrated differs only slightly from unit 15 above described and functions in substantially the same manner. Certain differences are, however, necessary in the construction of the frame of the unit and the relationship of various parts. It should be noted in this connection that the two hook shafts 24, one for each of the two units, have their axes in the same vertical plane transverse to the line of stitch formation and both of these shafts are revolved in the same direction. As a result of this, the hook beak of the unit 15 is arranged to seize the needle thread loop 29 while the beak is moving in the direction of feed of the work while the hook beak of the unit 18 is arranged to travel at this time in a direction counter to the direction of feed of the work. This, of course, means that the cams 40 for the two units must turn the bobbin holders in the same direction about their axes to provide the gap between the projection 35 and the cooperating shoulder on the throat plate at the proper time, but in doing so the projections are actually moved in reverse directions, i.e., one in the direction of feed and the other counter to the direction of feed. This necessitates a slightly different location of the ribs on the throat plate 39 which cooperate with the projections 35 of the two bobbin holders, as shown in Fig. 9. The projection 35 of the bobbin holder for unit 18 is urged by the frictional drag of the rotating hook body against the adjacent shoulder on the rib 38a and the projection is shifted by the cam toward, but not quite against, the adjacent shoulder of the rib 37a.

Suitable work feeding mechanism is provided for advancing the work along the throat plate in the course of stitch formation. It is important that this be constructed and arranged in such a manner as not to interfere with the above-described adjustment of the positions of the two hook units toward and away from each other to bring about either a relatively close spacing of the two lines of stitching formed thereby or a relatively wide spacing of these lines of stitching. For this purpose the work feeding mechanism, which is interposed between the two units 15 and 18, may suitably be of the character disclosed in the above-mentioned Quist and Cottrell patents. It may comprise a feed dog 52 (Fig. 11) having a downwardly extending shank 53 arranged to be secured by a screw 54, in an appropriately adjusted vertical position, in a channel formation 55 provided in a feed bar 56. The vertical position of the feed dog 52 may be readily and accurately adjusted by means of a screw 57 cooperating with the lower end of the shank 53 of the feed dog. In the course of such adjustment the screw 54 will be loosened and then retightened when the adjustment is accomplished. At its rearward end (to the left in Fig. 11) the feed bar 56 is pivotally connected by means of a pin 58 with the lower end of a pitman 59 having a strap surrounding an eccentric 60 secured to the rotary shaft 11. It will be apparent that through this connection the indicated end of the feed bar will be lifted and lowered upon each revolution of the shaft 11 and thus lift and lower the feed dog in rela-

tion to the openings in the throat plate 29. At its opposite end the feed bar 56 is pivotally mounted, by means of a rod or shaft 61, on the upper end of a feed rocker 62. The latter is secured to the rock shaft 14 which, as previously explained, is rocked by connections from the top rotary shaft. As shown in the Quist patent mentioned, the connections for this purpose may be coordinated with connections for imparting a needle feed action to the needle bar of the machine. Feed and return movements are thus imparted to the feed dog. As will be seen from Figs. 2, 6 and 7, the construction of the hook units 15 and 18 and of the feed mechanism just described is such that the two rotary hook bodies may be brought quite closely together to make possible the formation of two closely spaced lines of lockstitches.

Turning now to Figs. 16, 17 and 18, there is disclosed a modified form of hook unit or saddle embodying the rotary cam construction of the invention. In this form of the invention a spiral gear 63 (Fig. 18) secured to the rotary drive shaft 11 in the base of the frame cooperates with a spiral gear 64 secured to a hook carrying shaft 65 of the unit. The latter at its upper end carries the rotary component 65a of the hook. Adjacent its lower end the shaft 65 has secured thereto a gear 66 which meshes with an idler gear 67 suitably journaled in the frame of the unit. This idler gear in turn meshes with a gear 68 of double the diameter of gear 66. Gear 68 is secured to the lower end of a shaft 69 which carries at its upper end a cam 70 which may be similar to and mounted in the same manner as the cam 40 of the first embodiment. It will be understood that gearing 63, 64 is such as to rotate the hook at double the angular speed of the shaft 11. In turn the gearing 66, 67 and 68 is such as to rotate the shaft 69 and the cam 70 at half of the angular speed of the rotary hook and hence at the same angular speed as the shaft 11. The construction of the hook and the action of the cam 70 thereon may be the same as described in relation to Figs. 1-15, inclusive.

In Fig. 19 there is shown a construction which may be the same as that shown in Figs. 16-18 except for the provision of a different gearing between the hook shaft 65 and the cam supporting and rotating shaft 69. In this modified construction the gear 66 secured to the hook shaft meshes with an idler gear 71 positioned somewhat differently from the idler 67 above described. Gear 71 meshes with a gear 72 having a diameter equal to that of gear 66. Gear 72 is secured to the lower end of shaft 69 and serves to rotate the same in the same direction as shaft 65 is being rotated and at the same angular speed as the latter. In this embodiment of the invention the cam 70 will be given a complete revolution for each revolution of the hook body 65a. In other respects the construction may be the same as previously described.

Figs. 20-23 illustrate a further modification of the invention. In this form, the means for rotating the cam which opens the bobbin basket or carrier is driven by connections from the main rotary shaft in the base independently of the means for driving the rotary hook. Thus, as shown, the machine is provided with a rotary drive shaft 73 journaled in bearing sleeves 74 and 75 carried by the base of the frame. Shaft 73 corresponds with shaft 11 of the first embodiment. A pair of hook units or saddles 76 and 77 is provided, one being mounted in the same manner as the unit 15 of Fig. 2 and the other mounted in the same manner as unit 18 of Fig. 2. Secured to the shaft 73 are two spiral gears 78, one for driving the hook carrying shaft in each of the units 76 and 77. These gears mesh with spiral gears 79 secured to the respective hook shafts 80 of the two units. Shaft 80 of each unit carries at its upper end a rotary hook 81 of the same construction described in relation to the first embodiment. Adjacent each of the spiral gears 78 there is secured to the shaft 73 or formed integrally therewith, a smaller spiral gear 82 which meshes with a spiral gear 83 of the related hook unit. For the unit 76, shown in

Fig. 22, the gear 83 is secured to a shaft 84 which carries at its upper end a cam 85 which may be of the same construction and mounted in the same manner as the cam 40 previously described. For the unit 77 the gear 83 is secured to a shaft 84a (Fig. 21) which at its lower end carries a toothed sprocket 86. The latter is connected by a toothed belt 87 with a toothed sprocket 88 secured to the lower end of a shaft 89 which is mounted in the hook unit or saddle and which carries a cam 90 at its upper end. This cam may likewise be of the same character as cam 40 and may be mounted on the shaft in the same manner. The gearing described is such that while each hook shaft 80 is rotated at double the angular speed of the shaft 73, the shafts 84, 84a and 89 will be driven at the same angular speed as the shaft 73. The construction and mode of operation of the form of the invention just described is in other respects just the same as the form shown in Figs. 1-15, inclusive. It will be appreciated that, if desired, the connections from the shaft 73 to the shafts 84 and 89 could be such that the latter would rotate at double the angular speed of the shaft 73 and thus at the same angular speed as the rotary hook carrying shafts 80.

In each of the foregoing embodiments it will be noted that the relationship of the hook shaft to the rotary cam shaft of the several units is the same. This relationship is such that it acts on the projection 35a of the top flange of the bobbin basket or carrier at a point about 135° back of the point at which the hook beak seizes the needle thread loop. For machines intended to be driven at especially high speed it has been found desirable to locate the point of contact of the cam with the indicated projection on the bobbin basket somewhat closer to the point at which the hook beak seizes the needle thread loop, preferably along a line somewhat less than 90° back of the latter point. Such an arrangement is shown in Figs. 24-29. It allows a somewhat greater part of a revolution of the hook in which to develop a gap for the passage of the needle thread loop between the cam and the basket projection on which it acts, after the cam has completed its function of turning the basket to open up the gap between the restraining shoulders which prevent the basket from rotating with the hook body. It also enables the use of a cam of somewhat different configuration, i.e., one having a smooth periphery with only one shoulder at the point between the maximum and minimum radii of the cam.

Referring now to Figs. 24-29, inclusive, there is shown at 91 the main rotary drive shaft in the base of the frame, this shaft corresponding with shaft 11 of the first embodiment. It is journaled in bearing sleeves 92 and 93 carried by the frame. Hook units or saddles 94 and 95 are carried by the frame in the same manner as the units 15 and 18 so that they may be adjusted toward and away from the line of stitch formation. Two spiral gears 96 are secured to the shaft 91 in a manner to permit their axial adjustment along the shaft to correspond with the location of the units 94 and 95. Each gear 96 meshes with a spiral gear 97 (Fig. 26) secured to a shaft 98 journaled for rotation about a vertical axis in the related unit and arranged to carry a rotary hook of the character above described. A gear 99 secured to the shaft 98 adjacent its lower end meshes with an idler gear 100 which is suitably journaled in the hook unit and which in turn meshes with a gear 101 secured to the lower end of a vertical shaft 102 which carries a cam 103 at its upper end. The preferred contour of cam 103 is shown in Fig. 29. It is arranged to cooperate with a triangular projection 104 at the top of the bobbin basket. It will be noted that when the projection 104 is permitted to ride from the high to the low point of the cam, the loop seizing beak 105 of the hook body is about 120° away from the projection 104. Also, it will be noted that the axis of the shaft 102 and the cam 103 is located in a vertical

plane through the axis of the hook shaft that is less than 90° back of the vertical plane which contains the axis of the hook shaft and the point at which the hook beak seizes the needle thread loop. These relationships insure adequate clearance between the projection 104 and the surface of cam 103 at the time the needle thread loop is being drawn from the hook by the usual take up mechanism and must be passed between the projection 104 and cam 103. The means for restraining rotation of the bobbin basket by the frictional drag of the rotating hook body may be the same as in the first embodiment and may comprise a projection 106 at the top of the basket arranged to fit into an opening provided between downwardly extending ribs 107 and 108 on the throat plate 107b. Considering the uppermost hook shown in Fig. 29, the projection 106 is normally urged against the adjacent shoulder of rib 108 by the frictional drag mentioned, and it is carried away from said shoulder and toward, but not quite into engagement with, a shoulder at 20 the adjacent end of the rib 107 by the action of the cam 103 at the proper time. For the hook at the bottom of Fig. 29, the projection 106 is urged by the frictional drag of the hook body toward the rib 107a and it is urged by the cam toward the rib 108a.

25 To enable adjustment of the units 94 and 95 into a position in which they are relatively close to each other and thus provide for the formation of two closely spaced lines of stitching, a feed bar 110 of slightly different shape from that designated 56 in the first embodiment is provided. Feed bar 110 is rockably mounted, by means of a sleeve portion 111 in the upper ends of arms 109 of a feed rocker, similar to member 62 shown in Figs. 2 and 11, which is arranged to be rocked by the oscillation of a shaft similar to the shaft 14 of Fig. 2. This serves 30 to impart the feed and return movements to the feed dog. The latter, as shown in Fig. 26, has a shank 113 arranged for vertical adjustment in a channel 112 provided in the feed bar 110 at an intermediate point. The active portion of the feed dog is indicated at 114 and the arrangement 35 is such that the relationship of this to the throat plate of the machine may be varied by the loosening of a clamping screw 115 which enables adjustment of the shank 113 of the feed dog in the channel 112. In front 40 of the feed dog carrying channel 112 of the bar 110 the latter is provided with a reversely curved portion 116 (Fig. 24) and the extreme forward end of the bar is pivotally connected by a pin 117 with a pitman 118 having a strap portion surrounding an eccentric 119 secured to the shaft 91. Through this connection the lifting 45 and lowering movements are imparted to the feed dog. 50 It will be noted that with the construction shown it is possible to locate the bobbin basket opening cam in a most favorable position and still enable adjustment of the two hook units 94 and 95 into closely spaced relationship.

55 I claim:

1. In a lockstitch sewing machine a frame having a work supporting base, a rotary drive shaft extending longitudinally of said base, a hook shaft, connections from 60 said drive shaft to said hook shaft for rotating the latter at twice the angular speed of the drive shaft, a rotary hook carried by said hook shaft, said hook having a rotary component secured to said hook shaft for rotation therewith and a bobbin carrier journaled within said rotary 65 component, said rotary component having a thread loop seizing beak, said carrier and said frame having cooperating shoulders for restraining said carrier against rotation with said rotary component in the normal stitch forming operation of the latter, a rotary cam adjacent said 70 bobbin carrier, said bobbin carrier having a surface thereon arranged to be engaged by said cam and acted upon by the latter to cause turning of said carrier counter to the direction of rotation of said rotary component to thereby disengage said shoulders to enable the passage of a branch 75 of the thread loop therebetween, and connections for

constantly rotating said cam in the same direction in pre-determined relation to the rotation of said hook shaft.

2. In a lockstitch sewing machine of the character set forth in claim 1 a rotary shaft arranged to carry and drive said cam, said last-mentioned connections comprising motion transmitting means interconnecting said hook shaft with said cam carrying and driving shaft.

3. In a lockstitch sewing machine of the character set forth in claim 1 a rotary shaft arranged to carry and drive said cam, said last-mentioned connections comprising motion transmitting means for driving said cam carrying shaft from said rotary drive shaft independently of said hook shaft.

4. In a lockstitch sewing machine of the character set forth in claim 1 a rotary shaft arranged to carry and drive said cam, said last-mentioned connections comprising a toothed sprocket on said hook shaft, a second toothed sprocket on said cam carrying and driving shaft, and a toothed belt interconnecting said sprockets.

5. In a lockstitch sewing machine of the character set forth in claim 1 a rotary shaft arranged to carry and drive said cam, said last-mentioned connections comprising a spiral gear on said rotary drive shaft, a second spiral gear meshing with said first-mentioned spiral gear, a sprocket connected for rotation with said second spiral gear, a second sprocket connected with said cam carrying and driving shaft, and a belt interconnecting said sprockets.

6. In a lockstitch sewing machine of the character set forth in claim 1 a rotary shaft arranged to carry and drive said cam, the periphery of said cam being such in relation to the surface of said carrier and in relation to said cooperating shoulders on said frame and carrier that said cooperating shoulders are arranged to restrain rotation of said carrier in a position in which clearance is provided between said cam and said surface on said carrier during a portion of each revolution of the cam.

7. In a lockstitch sewing machine of the character set forth in claim 6, means enabling adjustment of said cam on said carrying and driving shaft in a manner to vary the extent of said clearance and the angle through which said bobbin carrier is turned by said cam.

8. In a lockstitch sewing machine of the character set forth in claim 1, said last-mentioned connections including means enabling angular adjustment of said cam in relation to said hook shaft to vary the timing of the action of said cam in relation to the timing of the action of said hook.

9. In a lockstitch sewing machine a frame having a work supporting base, a throat plate in said base, a thread carrying needle reciprocable toward and from said base and adapted to carrying a needle thread loop through said throat plate, a rotary drive shaft extending longitudinally of said base, a hook shaft journaled in said base, connections from said drive shaft to said hook shaft for rotating the latter at twice the angular speed of the drive shaft, a rotary hook carried by said drive shaft, said hook having a rotary component secured to said hook shaft for rotation therewith and a bobbin carrier journaled within said rotary component, said rotary component having a beak adapted to seize said needle thread loop beneath said throat plate, said carrier and said throat plate having cooperating shoulders for restraining said carrier against rotation with said component in the normal stitch forming operation of the latter, a rotary cam adjacent said bobbin carrier arranged to engage a surface thereon for turning said carrier counter to the direction of rotation of said rotary component to provide a gap between said shoulders, a shaft parallel with said hook shaft for carrying said cam, said cam carrying shaft being so disposed in relation to said hook shaft that the point of coaction between said cam and said surface is not more than 150° back of the point at which said beak seizes said needle thread loop, and means for con-

stantly rotating said cam carrying shaft in the same direction in predetermined relation to said hook shaft.

10. In a lockstitch sewing machine of the character set forth in claim 9, said cam carrying shaft being so disposed in relation to said hook shaft that the point of contact of said cam with said surface is less than 90° back of the point at which said beak seizes said needle thread loop.

11. A lockstitch sewing machine adapted to form two parallel lines of lock stitches in predetermined spaced relation which comprises a frame having a work supporting base, a throat plate in said base, a pair of thread carrying needles reciprocable toward and from said base and adapted to carry needle thread loops through said

15 throat plate, a rotary drive shaft extending longitudinally of said base, a plurality of hook units mounted in said base and adjustable toward and away from each other in a direction parallel with said shaft, each of said units having a vertically disposed hook shaft, means connecting

20 said drive shaft with said hook shafts for driving each of the latter at double the angular speed of said drive shaft, a rotary cam carrying shaft in each of said units parallel with the hook shaft therein, means for rotating said cam shafts constantly in the same direction at a

25 speed correlated to that of said hook shafts, a rotary hook carried by each of said hook shafts, each hook comprising a rotary component and a bobbin carrier journaled within said rotary component, means on said throat plate providing a pair of shoulders each cooperat-

30 ing with a shoulder on one of said bobbin carriers to prevent rotation thereof with its related rotary component in the normal stitch forming operation of the latter, a cam carried by each of said cam carrying shafts arranged to engage directly the bobbin carrier of the

35 related unit to turn said bobbin carrier slightly in a direction counter to the direction of rotation of the rotary component of said unit, work feeding mechanism for advancing work across said throat plate for cooperation with said rotary hooks, said work feed-

40 ing mechanism comprising a feed bar having a longitudinally extending portion positioned between said hook units and disposed beneath said throat plate, and connections from said drive shaft for imparting four motion movements to said feed bar.

45 12. In a lockstitch sewing machine of the character set forth in claim 11, said throat plate having openings therethrough for the passage of said needles in the region of said shoulders thereon, said rotary components of said back-needle having a hook adapted to seize a related

50 said hooks each having a beak adapted to seize a related needle thread loop, each of said cam carrying shafts having its axis disposed in a plane passing through the axis of its related hook shaft which is at an angle of less than 150° to a plane containing the axis of said hook shaft and also the point at which said beak seizes the needle thread loop in a direction back from said point.

13. In a lockstitch sewing machine of the character set forth in claim 12, said planes being disposed at an angle of less than 90° in relation to each other.

60 14. In a lockstitch sewing machine of the character set forth in claim 13, said feed bar being of reverse curve configuration in the portion positioned between said hook units.
